UNITED STATES PATENT OFFICE

KATHERYNE L. JOHNSTON, OF CHICAGO, ILLINOIS

ARTICLE ATTACHING DEVICE

Application filed March 30, 1929. Serial No. 351,149.

This invention relates to article attaching device and has for its object to provide, alone or in combination with an article to be attached, a device which may be readily applied to such article and the material to which it is affixed and may with equal ease be detached therefrom.

Another object is to provide a device of this character which may be cheaply and readily manufactured and utilized with buttons of present day construction.

Another object is to provide an attaching device of the character indicated which is also provided with a guard or sheath to cover the penetrating point after attachment or when not in use.

These and other objects will be more fully described and set forth in the following specification and shown in the accompanying drawings, in which Fig. 1 is a plan view showing a button attached to a piece of fabric by an attachment device embodying my invention.

Fig. 2 is an inverted view similar to Fig. 1 showing the guard means in non-engaging position.

Fig. 3 is a vertical section along the line 3—3 of Fig. 1.

Fig. 4 is a perspective of an embodiment of my attaching device.

Like numerals refer to like elements throughout the drawings, in which 10 designates generally an attachment device comprising a stem portion 11 formed at its outer end with a spirally curved angularly disposed portion 12 having a free end 12—a preferably pointed or formed for ready penetration of fabric or other material. Intermediate its extremities the stem 11 is looped 40 11—a to form a spring connection for a parallel or reversely bent portion 13, at the outer end of which is provided a sheath or guard member 14 having the groove 14—a therein (see Fig. 3).

In Figs. 1 to 3 I have illustrated the method of attachment of a button to fabric with my device, 15 indicating a portion of the fabric such as the cloth of an overcoat. 17 indicates a button of conventional construction having a pair of spaced attachment aper-

tures 17—a, 17—b, this being of conventional construction.

In use the button may be laid against the fabric to which it is to be attached and held against the same by grip of the fabric and button between the thumb and the forefinger of one hand. The attachment member is located at the under side of the fabric and is operated so that the point 12—a will first pierce the fabric beneath the aperture 17—b for example, after which the stem 11 is rotated and the point passes through the other aperture 17—a and reversely penetrates the fabric, being brought to final position as illustrated in Fig. 2. The portion 13 may then be moved over to slip the guide 14 over the point 12—a as illustrated in Fig. 3 which completes the attachment of the button and sheathes the point against catching or piercing other material or objects which would otherwise come in contact with it.

The rotative movement of the stem 11 in most installations requires that the fabric be partially folded about the button to permit passage of the portion 13 from one side of the button to the other, which operation is quite obvious in the use of my device. This renders it desirable to make the length of the portions 11 and 13 sufficient to extend beyond the rim of the button to accommodate such fabric as is folded partially about the button in the application of the device, although the portion 13 may be straightened to alignment with stem 11 for free rotation without folding of the fabric.

The device is readily usable with any type of button, whether provided with two or with more apertures, it being obvious that the diameter of the curved or spirally formed portion 12 should approximate the distance between the centers of the button apertures to be utilized.

Variation may be made in the dimensions and arrangement to accommodate such conditions as may be met with in use.

It will be apparent that my device is susceptible of modification and departure from the form illustrated and described and I do not wish to be restricted to such form except

as it falls within the scope of the appended claims.

What I claim is:

1. An article attaching device comprising a stem portion and a curved engaging member angularly disposed with respect to said stem portion, said engaging member having an end to penetrate material and successively pass through a pair of apertures in an article, the curve of said member being of a diameter substantially the distance between the centers of said apertures. 5
2. An article attaching device comprising a stem portion and a curved engaging member angularly disposed with respect to said stem portion, said engaging member having an end to penetrate material and successively pass through a pair of apertures in an article, the curve of said member being of a diameter substantially the distance between the centers of said apertures, and a guard member engageable with said curved member to sheathe the penetrating end thereof. 10
3. An article attaching device comprising a stem portion and a curved engaging member angularly disposed with respect to said stem portion, said engaging member having an end to penetrate material and successively pass through a pair of apertures in an article, the curve of said member being of a diameter substantially the distance between the centers of said apertures, said device being further provided with a guard member flexibly attached to said stem and engageable with said curved member to sheathe said penetrating end. 15
4. An article attaching device comprising a spirally formed engaging portion, a stem angularly disposed with respect thereto and a portion carried by said stem and provided with guard means engageable with said engaging portion. 20
5. An article attaching device comprising a spirally formed engaging portion, a stem angularly disposed with respect thereto and a portion resiliently carried by said stem and provided with guard means engageable with said engaging portion. 25
6. An article attaching device comprising a curved engaging portion, a stem angularly disposed with respect thereto, said stem being spirally wound intermediate its extremities and provided with a reversely directed portion, said last named portion being provided with guard means for engagement with said curved portion. 30
7. In combination an article for attachment having a pair of spaced apertures there-through, an attaching device comprising a curved engaging portion and a stem, said engaging portion being constructed and arranged to pass through material, successively through the apertures in said article, and thereafter again through said material to attach said article thereto. 35

8. In combination an article for attachment having a pair of spaced apertures there-through, an attaching device comprising a curved engaging portion and a stem, said engaging portion being constructed and arranged to pass through material, successively through the apertures in said article, and thereafter again through said material to attach said article thereto, and a guard means associated with said device engageable with the curved portion after attachment of said article thereby. 70

9. In combination an article for attachment having a pair of spaced apertures extending there-through, an attaching device comprising a spiral engaging portion and a stem angularly disposed with respect thereto, said engaging portion being constructed and arranged to pass through material to which said article is to be attached, successively through said apertures and thereafter again through said material for attachment of said article thereto. 80

10. In combination an article for attachment having a pair of spaced apertures extending there-through, an attaching device comprising a spiral engaging portion and a stem angularly disposed with respect thereto, said engaging portion being constructed and arranged to pass through material to which said article is to be attached, successively through said apertures and thereafter again through said material for attachment of said article thereto, and guard means carried by said device to engage said engaging portion after attachment of said article. 90

In witness whereof, I hereunto subscribe my name.

KATHERYNE L. JOHNSTON.
